UNITED STATES PATENT OFFICE.

THOMAS CARROLL, OF DAYTON, OHIO, ASSIGNOR TO THE NATIONAL CASH REGISTER COMPANY, OF DAYTON, OHIO, A CORPORATION OF OHIO, (INCORPORATED IN 1906.)

CASH-REGISTER.

1,202,800.

Specification of Letters Patent. Patented Oct. 31, 1916.

Application filed January 27, 1913. Serial No. 744,437.

To all whom it may concern:

Be it known that I, THOMAS CARROLL, a citizen of the United States, residing at Dayton, in the county of Montgomery and State of Ohio, have invented certain new and useful Improvements in Cash-Registers, of which I declare the following to be a full, clear, and exact description.

This invention relates to multiple totalizer cash registers and one of the objects of the invention is to provide improved differential mechanism for selecting desired ones of the totalizers for operation.

Another object of the invention is to provide improved key controlled positive differential mechanism for operating totalizing devices.

Another object of the invention is to provide improved positively operated transfer mechanism.

Another object of the invention is to provide transfer mechanism coöperating with complementary movable members one of which is an actuator for accounting devices, which transfer mechanism controls certain relative movements between the said members for the purpose of effecting carrying operations.

Another object of the invention is to provide a construction of differential mechanism adapted to operate simultaneously a plurality of totalizers and to effect carrying operations therein by additional movements of the differential mechanism, but still wherein the additional movements effect only the desired totalizer or totalizers.

Another object of the invention is to provide an improved indicator setting mechanism.

Another object of the invention is to provide key controlled means for selecting for operation a totalizer from a plurality of totalizers, by a minimum movement of the totalizers.

Another object of the invention is to provide improved mechanism for determining the duration of engagement between the totalizers and their actuating devices for purposes of addition or total printing.

With these and incidental objects in view, the invention consists in certain novel features of construction and combinations of parts, the essential elements of which are set forth in the appended claims, and a preferred form of embodiment of which is

hereinafter described with reference to the drawings which accompany and form part of the specification.

Figure 1 is a transverse vertical section of a registering machine constructed according to the invention. This view represents a section at the side of one of the banks of value keys. Fig. 2 is a similar sectional view taken at the side of a bank of keys for controlling total and subtotal printing operations. Fig. 3 is a similar section taken at the side of a bank of department keys controlling the selection of totalizers. Fig. 4 represents a view in elevation of the right side of the machine with the casing removed. Fig. 5 is a front elevation of the left hand side of the machine showing the slip printing mechanism. Fig. 6 is a transverse vertical section in left elevation of the machine taken on the line 6—6 of Fig. 5. Fig. 7 is an enlarged detail of one section of the differential mechanism and totalizing devices controlled thereby. Fig. 7^A is an enlarged detail view of the main totalizer and coöperating mechanism. Fig. 7^B is a sectional detail of the totalizer taken on the line A—A of Fig. 7^C. Fig. 7^C is a detail in front elevation of one denominational section of the main totalizer. Fig. 7^D is a detail showing how movement of a totalizer is limited on resetting operations. Fig. 8 is a detail in right side elevation of the multiple totalizer unit. Fig. 9 represents a left side elevation of said totalizer unit. Fig. 10 is a fragmentary front view partly in section of the left end of the multiple totalizer unit. Fig. 11 is a detail in right side elevation of part of the key release mechanism and the mechanism under the control of a bank of total printing keys which is employed to release the differential mechanism on total printing operations. Fig. 12 represents a front view of the pitmen for controlling engagement of the totalizers with their actuators, and the cams for operating said pitmen. Fig. 13 is a right side elevation of the mechanism for engaging the totalizers with their operating devices. Fig. 14 is a view similar to Fig. 13 but showing only that part of the selecting mechanism which is employed to engage the totalizers with their actuating devices when additions are made to the totalizers. Fig. 15 shows that part of the totalizer selecting mechanism which is employed when subtotals are

printed as controlled by the totalizers. Fig. 16 is a view showing that part of the selecting mechanism which is employed when totals are printed and the totalizers are reset. Fig. 17 is a plan view of a sales slip supporting table. Fig. 18 represents a left side view of an adjustable stop device for the sales slip. Fig. 19 is a detail in right side elevation of gearing by which differential movement is transmitted to type carriers, and which permits the type carriers to remain in set positions for a desired length of time after the differential mechanism of the machine is restored to normal position. Fig. 20 is a detail in left side elevation of the sales slip feeding mechanism. Fig. 21 shows details of a sales slip as printed by the machine but before the stub part is cut from the remainder of the slip. Fig. 22 is a transverse vertical section showing indicator setting mechanism but with the differential mechanism modified to be movable vertically instead of horizontally as shown in the remaining views, and also to operate a totalizing device different in design from that shown in the remaining views. Fig. 23 is a detail in left side elevation of the mechanism for driving the differential mechanism shown in Fig. 22.

30 The cash register shown in the drawings is constructed to add item amounts on selected ones of department totalizers and on one grand totalizing device. A printing mechanism is provided wherein these items are printed in triplicate on inserted sales slips. The type carriers are set by the differential mechanism of the machine, normally controlled by banks of keys but which may be controlled by the totalizing devices 40 for the purpose of setting the type carriers to print totals.

45 The differential mechanism employed in the present invention comprises a plurality of pairs of members, differentially movable with respect to each other, but the total of the movement of each pair is constant. There is one pair of members or slides for each bank of keys and the keys control the relative movement between the members so 50 that upon the movement of the slides one of them may actuate to the desired extent, a corresponding element or elements in totalizing devices. The slides of each pair are driven in the same direction by a pinion located between and in engagement with racks carried by the slides. The pinions are loosely journaled on a shaft which is reciprocated radially to its axis and consequently moves the pinions bodily so that they carry 55 both of the slides in the same direction. The slides are provided with stepped shoulders which are engaged, and the slides thereby stopped, by depressed keys. The steps on the two slides normally are in such relative 60 location to each other that when the step on

one slide engages a key the corresponding step on the remaining slide will not engage the key until the total movement of the two slides amounts to some predetermined and constant value. Thus, if one slide is stopped 70 after having made one unit of movement, its companion slide will not engage the key until it has moved the complement of the one unit, namely, eight units of movement. This principle of differential mechanism 75 permits it to carry any desired load at any desired velocity, as the cams which are employed to reciprocate the pinion carrying shaft may be designed to bring this shaft to a stop at the limits of its movement as gradually as desired. This mechanism therefore obviates all possibility of overthrow or undue strain therein or in the devices operated thereby. For the same reason it is well adapted for positioning multiple totalizer 80 units, such as reels, for the purpose of selecting a totalizer for operation. Heretofore no multiple totalizer selecting mechanism has been provided which is well adapted for differentially rotating a totalizer carrying reel 90 by power supplied from the main drive shaft of the machine. This was due to the considerable necessary weight of the reel and its consequent inertia.

95 As above stated the stepped slides are controlled in their forward movement by the keys. When these slides are at rest in their extreme forward position, the desired totalizer or totalizers are engaged with rack teeth cut in one of the slides, and then the 100 slides are returned to normal position by the return movement of the aforesaid pinion supporting shaft and in this manner the extent of differential movement of one of the slides is communicated to the totalizing devices. The slides are stopped in their zero 105 positions by small pivoted levers or plates which are in position to be engaged by pins carried by the slides. By arranging the totalizer pinions to control adjustment of the 110 said levers or plates angularly, relative movement between the slides on their return may be controlled for the purpose of effecting carrying operations from one totalizer pinion to another. Thus if one slide is 115 stopped one unit of its movement before it reaches normal position, its companion slide will be permitted to pass its normal position one unit and therefore add an additional unit on its respective totalizer pinion. The 120 transfer plates or levers are controlled in their angular positioning by the totalizer elements positively without the use of springs.

125 From the foregoing it will be seen that the present invention provides a simple, reliable and positively operated transfer mechanism.

130 A construction is also provided wherein two totalizing devices may be simultaneously

actuated by the same set of actuators which have the additional unit of movement for purposes of transferring, but still do not prevent independent transfer operations in each totalizer. The particular method employed for accomplishing this end is that while a transfer operation is taking place in one totalizer the other totalizer is moved bodily with the rack which is effecting the transfer and consequently the transfer occurs only in the totalizer which remains stationary. Then the latter totalizer is unmched from the racks and the totalizer which has not yet performed a possible required carrying operation is returned to its normal position and is thus moved relatively of its actuating racks and at such time may be rotated for effecting transfers, as explained in detail farther on.

Driving mechanism.—In Fig. 4 are shown the two main drive shafts 1 and 2 geared to a pinion 3 fast to a crank 4. A large intermediate gear 5 pivoted on a stub shaft 6 serves to transmit motion from pinion 3 to a gear 7 fast to shaft 1 and a gear 8 fast to shaft 2. Each operation of the machine requires one rotation of shafts 1 and 2, consequently from the gear ratio shown in Fig. 4 it is necessary to revolve the crank handle twice to effect this single rotation of the drive shafts.

At the end of an operation the driving mechanism is stopped at the proper position by a pawl 9 engaging a shouldered plate 10 riveted to gear 7. As this pawl normally prevents forward rotation of the driving mechanism, in order to release the driving mechanism the crank is moved backward slightly thus causing the shouldered plate 10 to move forward slightly and thereby release pawl 9 which then moves upwardly as urged by its spring 11. Then the crank is caused to make two rotations in a forward direction at the end of which time a pin 12 on gear 7 strikes a bent extension 13 of pawl 9, rocking the pawl back into stopping position.

Keyboard.—The operating mechanism of the machine is controlled by a plurality of banks of value keys 101 (Fig. 1), a bank of department keys 102 (Fig. 3) and a bank of total keys 103 (Fig. 2). The purpose of the value keys is to control differential mechanism for operating the totalizing devices, and the type carriers of a slip printing mechanism, and the object of the department keys is to control mechanism for rotating a totalizer carrying reel to operatively position any totalizer with relation to the differential mechanism. The purpose of the total keys is to control the machine for printing totals or subtotals from either the main totalizer or one of the department totalizers.

The value keys 101 are slidably mounted in key frames 104 and are depressible against

springs 105 compressed between pins 106 on the keys and flanges 107 of the key frames.

To prevent the depression of more than one key at a time in any bank, the pins 106 coöperate with disks 108 loosely supported at the sides of the keys between the keys and a key detent 109. The end disks 108 have circular openings 110 through which pass pins 111 fastened to key frame 104 and these openings are of such size as to permit only slight free play between the disks, thus permitting the depression of only one key at a time.

In order to retain depressed keys in depressed position during the operation of the machine, the detents 109 are slidably mounted in the key frames 104 and are provided with a plurality of inclined slots 112 located in the path of movement of pins 106 on the keys. Therefore when a key is depressed the plate is shifted in the direction of its length, the slots being inclined so as to cause the plate to move forwardly against the action of its spring 113 interposed between a lug 114 on the detent and a lug 115 on corresponding frame 104. For the purpose of retaining the detents and thus the keys in their moved position and simultaneously releasing desired elements of the differential mechanism, pawls 116 are provided, journaled on a shaft 117 at their rear ends which are bent into yoke form to bear on the shaft at two points. Springs 118 are extended between pins 119 on the pawls 116 and a tie bar of the machine and serve to urge the pawls to rock upwardly. Pins 120 on the pawls normally bearing on the under side of lugs 114 of the detent prevent upward rocking of the pawls until the detents have been moved forwardly by depression of keys. Then the upward movement of pawls 116 serves to position pins 120 at the rear of lugs 114 and thereby retain the detents in their forward position and consequently the depressed keys are retained in depressed position. Each pawl 116 is further provided with a bent flange 121 for co-operating with a pin 122 on an actuator 200 of the differential mechanism for the purpose of normally preventing operation of the actuator and permitting its operation only on the depression of a key in its corresponding bank.

Each bank of keys is provided with a release key in order that keys which are depressed by mistake may be released without operating the machine. One of the release keys for the value banks is indicated by numeral 124 in Fig. 1. The release key for department keys is indicated by numeral 125 (Fig. 3) while the release key for the bank of total keys is indicated by the numeral 126 (Fig. 2). These keys are depressible against the actions of springs, as are the remaining keys and are in po-

- sition to engage pins 119 on the pawls 116 and thereby rock the pawls back to normal position and thus cause their pins 120 to be moved out of engagement with shoulders 114 on the key detents, permitting the detents to spring back to normal position under the action of springs 113 and thus permit the depressed keys to rise to normal position under the action of their springs.
- 10 The construction of the department keys and their mounting is similar to the value keys except that there are only four keys in the department bank besides the release key for such bank.
- 15 The department keys control means for releasing the machine for operation and for this purpose the key detent 127, for this bank, has a forwardly extending part 128 for engaging an upwardly extending arm 129 fast to a rod 130 journaled in brackets of a tie bar 131. A latch pawl 132 fastened to rod 130 normally engages a shoulder 133 on a disk 134 fast to drive shaft 2. A spring 135 holds latch pawl 132 in engagement with disk 134 but when a department key is depressed detent 127 in being forced forward rocks the arm 129 forward and thereby shaft 130 and through it pawl 132 is disengaged from the disk permitting the 20 driving mechanism of the machine to operate.
- 25 The machine release may also be operated by depressing a total key. When a total is printed from the main totalizer it is not desired to depress one of the department keys. For this reason shaft 130 (Fig. 2) is provided with an arm 136 similar to arm 129 and coöperating with a forward extension 137 of the detent 138 for the bank of total 30 keys thus effecting release of the machine when either of the total keys is depressed.
- 35 For the purpose of releasing depressed value keys after the same have performed their required functions, during an operation of the machine, shaft 117 (Fig. 1) is provided with a plurality of arms 139 fast to the shaft and located in position to engage the rear of pawls 116 at their yoke shaped ends and thus rock the pawls back to 40 normal position and permit the detents to return to normal position and the keys to rise under the action of their springs. In order to rock shaft 117 at the required time, it carries fast an arm 140 (Fig. 11) provided with a pin 45 141, normally engaged by a notch 142 in a pitman 143 having a roller 144 extending into a groove 145 in a disk 146 fast to shaft 1. The pitman 143 is forked at its lower end to be guided by shaft 1 and at its upper end is provided with a slot 147 through 50 which extends a pin 148 fast to a lever 149 pivoted on shaft 1 and having at its upper end a slot 150 through which extends a pin 151 fast to the detent 138 for the bank of 55 total keys. The pitman 143 is thus guided in its movement by the pin 148 on lever 149 in order to provide means whereby the pitman may be made inoperative on the depression of total keys, as explained farther on. When the pitman 143 is drawn downwardly 70 it rocks shaft 117 through the arm 140 causing the arms 139 on shaft 117 (Fig. 1) to engage the yoke shaped rear ends of pawls 116 and thereby rock the forward ends of the pawls downwardly out of engagement 75 with the key detents, which then spring back to normal position and simultaneously permit depressed keys to return to their upper positions.
- 80 The department and total keys are released independently of the value keys in order that shaft 117 may be employed at the beginning of total printing operations to rock the pawls 116 (Fig. 1) downwardly from their normal position as shown in this 85 figure for the purpose of releasing the actuators 200. To this end, shaft 117 with respect to the department and total keys (Figs. 3 and 2) respectively is not provided with arms for restoring the pawls 116 of these 90 banks, but instead a rod 152 is provided, journaled in the side frames of the machine, and having a pair of arms 153 located in vertical planes with and above pawls 116 95 operating with the department and total 100 banks. Rod 152 (Fig. 2) carries fast an arm 154 to the forward end of which is pivoted a pitman 155 having its lower end forked over shaft 1 to be guided thereby. The pitman 155 is provided with a roller 156 extending into a groove 157 in a cam disk 158 fast to shaft 1. The cam groove is formed to draw the pitman downwardly near the end of each rotation of shaft 1 and accordingly at this time through arm 154 the shaft 152 is 105 rocked counter-clockwise carrying its arms 153 into engagement with the pawls 116 for the total and department banks (Figs. 2 and 3). In this manner depressed keys in these 110 banks are released independently of the value keys.
- 115 In order that value keys may not be depressed when one of the total printing keys 103 (Fig. 2) is depressed, the detent 138 for the total keys has a pin 188 passing through a slot 189 in an arm 190 fast to a shaft 191 journaled in the machine frames and cut away at 192 (Fig. 1) where the shaft is in the path of movement of detents 109 for the value keys. Consequently when a total key 120 is depressed the forward movement of detent 138 through the pin 188 rocks arm 190 counter-clockwise, thereby rocking shaft 191 so that the cut away parts of the shaft are moved out of the path of detents 109. It is 125 then impossible to depress a value key as detents 109 cannot move forwardly. Also when a value key is depressed the lower end 193 of the corresponding detent rests in the cut out part 192 of shaft 191 and prevents 130

the rocking of the shaft. In this manner depression of a value key prevents the depression of a total key and therefore when amounts are set on the keyboard it is impossible to effect a total printing operation.

Differential mechanism.—The differential mechanism besides the keyboard, is divided into three sets of mechanisms, namely, a plurality of amount determining actuators 10 shown in Figs. 1 and 7, a set of racks for rotating the totalizer carrying reel and controlled by the department keys (Fig. 3), and devices for determining total and subtotal printing controlled by the total keys 15 (Fig. 2).

The purpose of the differential mechanism under the control of the value keys is to differentially rotate selected totalizers and position amount type carriers of the printing mechanism, while the purpose of the differential mechanism under the control of the department and total keys is also to position corresponding type wheels in addition to their functions of selecting department totalizers for operation, and determining total and subtotal printing operations.

The differential mechanism under the control of the value keys comprises for each bank a pair of slides 200 and 201 having slots 202 through which pass shafts 203, 204 and 205 journaled in the frames of the machine. Thus these shafts serve to guide the pairs of slides 200 and 201 in their horizontal movement. A rod 206 passes through slots 207 in the slides and is secured to the upper ends of arms 208 fastened to a shaft 209 journaled in the frames of the machine. On the rod 206 are journaled a plurality of pinions 210 each engaging a rack 211 on a slide 201 and a rack 212 on its companion slide 200. The arms 208 are provided with rollers 213 extending into grooves 214 cut in cam disks 215 fast on drive shaft 1. Each slide 200 is provided with rack teeth 216 by means of which movement of these slides 200 is communicated to the main totalizer and to a selected department totalizer and to type carriers in the printing mechanism.

In operation cams 215 rock the arms 208 around the shaft 209 to carry the upper ends of the arms forwardly and then return the same to the position in which they are shown in Fig. 1. The forward movement of rod 206 would, if no key were depressed, cause the pinions 210 to roll along rack 212 fast to the slide or actuator 200, as the slide would be retained in its normal position by pawl 116 engaging by flange 121, pin 122 on the slide. This rolling movement of pinion 210 results in a forward movement of slide 201 from the teeth of pinion 210 engaging and driving rack 211. Thus the actuators 200 remain in normal position and the operation is idle if no key has been depressed. When a key in any bank is de-

pressed, the pawl 116 for such bank is permitted to spring upwardly because of the forward movement of the respective key detent 109 resulting in shoulder 114 passing away from pin 120 on the pawl. This movement of the pawl carries flange 121 above pin 122, and, therefore, when the arms 208 are rocked forwardly both slides 200 and 201 are carried forward until one of stepped shoulders 217 or 218 of the slides engages 75 the shank of a depressed key whereupon such slide is prevented from further forward movement and its companion slide is carried forward until one of its shoulders 80 engages the depressed key. The shoulders 217 and 218 are so positioned on the slides that the slide 200 moves forwardly an extent corresponding in value to the depressed key while the slide 201 moves the complement of such value, and therefore the movement of both slides is, combined, of constant value. For instance, the shoulder on actuator 200 which coöperates with the "one" key is normally spaced from the key so that when moved into engagement therewith the actuator will be moved the distance of one tooth space of the rack 216. The corresponding shoulder on the companion plate or slide 201 is located the distance of eight of these tooth spaces away 95 from the "one" key, consequently the two slides together move nine spaces. If the "two" key is depressed, actuator 200 will move two spaces while companion plate 201 will then move only seven spaces. Accordingly the movement between each pair of plates is always complementary, the plates together always moving nine spaces. In this manner while the movement of each pair of plates is of constant value the relative movement between the plates may be varied as required to perform different operations.

Fig. 3 shows in side elevation the bank of department keys and connections controlled thereby for rotating a reel 350 for the purpose of bringing one of the department totalizers 351 into operative relation with the racks 216 on actuators 200 (Fig. 1). As shown in Fig. 3, there are four department keys and the usual release key in the bank. The department keys control differential relative movement between a pair of slides 219 and 220 in the same manner as the slides 201 and 200 (Fig. 1) are controlled by the value keys, but with respect to slides 219 and 220 it is desirable that they differentially rotate the reel 350 at the beginning of an operation of the machine and leave it in its adjusted position irrespective of the restoring movement of the slides. Therefore in order that the slides will not uselessly return the reel to normal position at the end of each operation of the machine, the slides operate to position the reel di- 125 130

rectly from one position to another on their forward movement and for this reason do not disturb the position of the reel between successive operations of the same totalizer.

5 In order that the above end may be accomplished, both of slides 219 and 220 are employed for rotating the reel 350. The connections are such that the forward movement of one slide rotates the reel in one direction while the forward movement of the other slide rotates the reel in the opposite direction.

10 Referring to Fig. 3, the slide 219 carries fast a rack 222 while slide 220 carries a rack 15 221. These racks engage on opposite sides with a pinion 223 journaled on a pin 224 carried at the upper end of an arm 225 pivoted on a rod 226. The arm 225 is provided with a roller 227 extending into a 20 groove 228 in a disk 229 fast to shaft 1.

The slide 220 is provided with slots 230 by means of which it supports loosely a rack 231 having pins 232 extending through slots 230 and meshing with a pinion 233 journaled 25 on shaft 205. The slide 219 is provided with slots 234 for supporting a rack bar 235 which is provided with pins 236 extending through the slots. The rack bar 235 has a set of rack teeth 237 engaging pinion 233 30 and another set of rack teeth 238 engaging an intermediate pinion 239 journaled on a stud 240 carried by a side frame of the machine and meshing with a pinion 243 fast to the reel supporting shaft 244.

35 The operation of the reel setting mechanism as controlled by the department keys, is that racks 221 and 222 are moved forwardly through forward rocking of arm 225 as controlled by cam 229. Thus a movement of 40 constant value is imparted to slides 219 and 220 through pinion 223 journaled on arm 225 and engaging racks 221 and 222 on the slides. When one of the slides is stopped by a shoulder thereon engaging a depressed key 45 the complement of its total movement is imparted to the companion slide by causing pinion 223 to roll along the rack 221 or 222 which has been stopped. At the end of each forward movement of slides 219 and 220 the 50 rear ends of slots 230 and 234 engage pins 232 and 236 carried by racks 231 and 235.

55 For instance, with the reel set as shown in Fig. 3, and if the machine is operated with the uppermost department key depressed, slide 219 will be retained in its normal position as shown in this figure and slide 220 will be permitted to move forwardly its full stroke or until the rear ends of slots 230 engage pins 232 but this will not result in a 60 movement of racks 231 or 235 and consequently the totalizer reel will remain in the position in which it is shown in the drawing. If the machine is operated, say, with the lowest department key depressed, then 65 both slides will be permitted to move for-

ward until their shoulders 241 and 242 engage the shank of the lowest department key. In this case forward movement of slide 220 is not sufficient to cause the rear ends of its slots 230 to engage pins 232 and 70 consequently will not move rack 231, but the rear ends of slots 234 in slide 219 being in engagement with pins 236 on rack 235, rack 235 will be moved forward until shoulder 241 of slide 219 engages the depressed department key. Movement of rack 235 rotates pinion 239 and consequently pinion 243 fast to the reel supporting shaft 244. In this manner the reel will be given three-fourths of a rotation, bringing opposite to 80 the actuating racks 216 (Fig. 1) the particular reel totalizer which is represented by the lowest key in the bank of department keys (Fig. 3).

85 The forward movement of rack 235 by rotating pinion 233 causes a rearward movement of rack 231 bringing it to such position that if, on the next operation of the machine, the same department key is depressed, rack 231 will not be moved, as would also be the 90 case with respect to rack 235, but if, on the next operation of the machine, some other department key is depressed, rack 231 will then be engaged and moved, its forward movement being communicated through pinions 233 to rack 235 and from it to the totalizer reel through the pinions 239, 243.

95 The bank of total keys controls a pair of slides 245 and 246 (Fig. 2) by means of 100 which totalizer engaging mechanism is controlled for engaging the totalizers with the actuating mechanism as required on total and subtotal printing operations. The bottom key in this bank is depressed when it is desired to obtain a subtotal from one of 105 the department totalizers; the second key from the bottom is depressed if it is desired to obtain a total from a department totalizer; the third from the bottom key is depressed if it is desired to obtain a subtotal 110 from the main totalizer and the uppermost key is depressed in order to obtain a total from the main totalizer.

115 The slide 246 controls engagement of the main totalizer for which purpose at its forward end it extends downwardly and is provided with a pin 247 extending through a slot 248 in a pitman 249 which has a horizontal slot 250 through which passes the supporting shaft 251 for the main totalizer. The pitman 249 also has slots 252 by which it engages pins 253 extending from the side of slide 246 to guide the pitman in a vertical movement which is given to it by means of one of the pitmen 254, 255 and 256 (Figs. 14, 15 and 16), suitably formed to lift the pitman 249 through the pins 257 and 258 extending from the side of the pitman. Differential movement of slide 246 through the pins 253 and 247 120

5 serves to position the pitman 249 into engagement with one of the pitmen 254, 255 or 256 and these pitmen are respectively operated by cams 2577, 2588 and 2599 fast to the drive shaft 2. The cams are constructed to rock their respective pitmen as required in order that the totalizer may be meshed respectively for addition or for subtotal or total printing.

10 For the purpose of controlling the time of meshing of department totalizers the slide 245 is provided with a downwardly extending part 260 on which is slidably mounted a pitman 261. The arm 260 has pins 262 passing through slots 263 in the pitman 261 for the purpose of supporting and guiding the pitman. The pitman is provided with a horizontal slot 264 into which passes a roller 265 (Fig. 10) mounted 15 on a stud secured to a totalizer meshing slide 266, the construction of which will be hereinafter described. Pitman 261 is provided with pins 267 and 268 as shown in Figs. 12 to 16, one of which is adapted to 20 be engaged by one of the pitmen 269, 255 or 256, depending upon the positioning of pitman 261 as controlled by slide 245.

25 If the slides 245 and 246, in an operation of the machine, are not influenced by a depressed total or subtotal key, the main totalizer and the selected one of the department totalizers will be engaged with the actuating mechanism during the required time for performing addition in these devices. At such time the pitmen 254 and 269 control the engagement, slide 246 remaining in normal position and slide 245 moving forward its entire stroke. If one of the total or subtotal keys is depressed the 30 slides 245 and 246 will be positioned to cause the selected totalizer to be engaged with the actuating mechanism for the purpose of total or subtotal printing depending upon the key depressed.

35 The slides 245 and 246 are driven by a cam 270 fast to shaft 1 (Fig. 2) and having a cam groove 271 coöperating with a roller 272 pivoted on an arm 273 in turn journaled on rod 226 fixed in the machine side frames. At its other end arm 273 is provided with a stud 274 on which is journaled a pinion 275 meshing with a rack 276 carried by slide 245 and a rack 277 carried by slide 246. The slide 246 is normally retained in the position in which it is shown in Fig. 2 by the pawl 116 coöperating with a pin 122 on the slide. When a key is depressed the detent 138 is shifted by a pin on the key engaging one of the inclined slots 40 of the detent in the manner that the value keys shift their respective detents. In this manner shoulder 114 on the detent is moved away from pin 120 on pawl 116, permitting the pawl to rock upwardly under spring 45 action and thereby release slide 246 which,

upon rotation of drive shaft 1, is driven forwardly by the oscillation of arm 273 until a shoulder on the slide engages a depressed key. Slide 245 at this time has a complementary movement to slide 246 and therefore the extent of movement of either slide may be controlled and one of the pitmen 249 or 261 positioned to be operated by a desired one of cams 2588 or 2599.

50 *Main totalizer.*—The main totalizer is indicated in various views by numeral 300 and its purpose is to add together the amounts of all transactions entered in the machine. It consists of a plurality of pinions loosely journaled on shaft 251 secured 55 to a pair of arms 301 (Fig. 1) journaled on a rod 302 passing through guide slots 303 in the frames of the machine. As before mentioned, the totalizer shaft 251 extends through slots 250 in pitman 249 (Fig. 2), 60 thus when pitman 249 is moved upwardly it engages shaft 251 and rocks the totalizer carrying arms 301 around shaft 302 meshing the totalizer pinions with the actuating racks 216 (Fig. 1).

65 To prevent accidental rotation of the totalizer pinions when disengaged from racks 216, a plate 304 (Fig. 7^a) having teeth 305 for engaging the totalizer pinions is provided. The plate 304 is supported by shaft 70 302 and suitably positioned to engage the totalizer pinions when the same are disengaged from racks 216.

75 When additions are made in the totalizer cam 2577 (Fig. 14) controls its engagement with the racks 216, for which purpose the cam 2577 is provided with a groove 280 engaging a roller 281 on the pitman 254. When subtotals are printed from the main totalizer cam 2588 (Fig. 15) controls its 80 engagement and when totals are printed from the main totalizer cam 2599 (Fig. 16) controls its engagement.

85 *Department totalizers.*—The department totalizers 351 are journaled on rods 352 carried by a reel 350 supported by the rod 244 journaled in upright frames 353 (Figs. 9 and 10). Rotation of the reel under the control of the differential mechanism shown in Fig. 3 serves to position the desired totalizer 90 opposite the actuating racks 216. When in such position rollers 354 on the supporting shaft 352 for the selected totalizer are located in curved cuts 355 in slides 266 mounted on the frames 353. One of the slides 266 95 is provided with a stud 265 fitting in the horizontal slot 264 of pitman 261 (Fig. 2). Each slide 266 (Fig. 10) is mounted on one of the frames 353 by screws 356 fast to the frames which pass through slots 357 in the 100 slides; also the slides are provided with teeth 358 engaged by teeth 359 on segments 360 fast to a shaft 361 journaled in the machine frames. Thus when pitman 261 (Fig. 2) is moved in a vertical direction it engages pin 105 110

265 (Fig. 9) on one of the slides 266 causing this slide and its companion slide to move as guided by their vertical slots 357, the slides being compelled to move together by the segments 360 on shaft 361. The time of shifting the slides 266 is controlled by cams 278, 2588 and 2599 (Figs. 14, 15 and 16) through pitmen 269, 255 and 256 which respectively control the engagement for addition, subtotal and total printing, and for this purpose have rollers 365, 366 and 367 coöperating with cams 278, 2588 and 2599 respectively.

15 The supporting frames 353 (Fig. 9) for the totalizer reel are provided with circular grooves 363 registering with the grooves 355 in the slides 266. These grooves engage the rollers 354 of the totalizers which are not in engaging position and consequently prevent 20 accidental movement of such totalizers radially of the supporting reel.

25 The alinement of department totalizers when not in engagement with the actuating racks is maintained by toothed members 364 (Fig. 2) secured to the reel supporting shaft 244 to rotate with the shaft. In this manner rotation of the totalizer pinions is prevented at all times except after being moved radially of the reel supporting shaft 244 into 30 engagement with the totalizer actuators.

35 *Transfer mechanism.*—The transfer mechanism is shown in Figs. 1, 7, 7^A, 7^B, 7^C, and 7^D. The object of the particular construction employed is to effect transfers in both the main and department totalizers by extra 40 units of movement of their actuating racks while employing these racks to simultaneously operate two totalizers, and further to employ positively operated mechanism for 45 such operations.

40 Referring to Fig. 7, movable with each totalizer pinion are disks 400, and 401 for coöperating with transfer pawls 403 and 404 journaled on shafts 203 and 205. Each 45 of the pawls is provided with a pin 405 for coöperating with an extension 406 of one of the disks 400 and the pawls are also provided with curved surfaces 407 and 408 coöperating with one of disks 401. The latter have notches 409 to be entered by projections 410 located between the curved surfaces 407 and 408 on the pawls. The slides 200 and 201 respectively carry pins 411 and 412 for engagement with the pawls when the 50 slides reach their home positions. Thus if the angular position of the pawls 404 is altered, for instance, by rocking them in a counter clockwise direction as would occur when extensions 406 engage pins 405, the 55 slide 201 would be stopped one unit of movement before reaching its home position and the slide 200 would be permitted to move one unit past its home position and it is in this manner that transfers are effected in department 60 totalizers, but in order that transfers 65

may occur independently in the main totalizer and in the department totalizers, means are provided for moving the main totalizer and its transfer pawls rearwardly at the time that an extra unit of movement of some 70 of the actuators occurs for transferring in the department totalizers. In this manner the extra movement takes effect only in the department totalizer after which it is then unmeshed and the main totalizer is shifted 75 forwardly and the transfer occurs in it or not depending upon the angular position of its transfer pawls 403 as explained farther on. As a matter of fact not all of the actuators are shifted at any one transfer operation, consequently when the main totalizer is moving rearwardly those of the actuators remaining stationary cause corresponding pinions in the main totalizer to rotate backwardly one unit. This unit is restored on 80 the return movement of the totalizer. When pinions of the main totalizer stand at zero, the corresponding disks 400 have their extensions 406 in engagement with the rear of pins 405 and therefore would prevent 85 backward rotation of the pinions as pawls 403 cannot rotate clockwise from normal position, pins 4031 preventing such movement. To overcome such possibility disks 400 are connected to their companion pinions of the 90 totalizer by springs 4001 (Fig. 7^C) so that the disks may be held in normal position while their companion pinions rotate one step backwardly. The disks 400 are loosely 95 journaled on the hubs of totalizer pinions 300, and are cut out at 4002. Through these cuts extend pins 4003, on the pinion hubs, which limit the amount of relative movement between the pinions and disks to that equal 100 to one tooth space of the pinions. On the 105 forward rotation of a pinion its pin 4003 engages a shoulder 4004 of disk 400, thus causing the latter to rotate with the pinion. Springs 4001 normally hold disks 400 with 110 their shoulders 4004 in engagement with pins 4003 but when a pinion stands at zero, the engagement of extension 406 with the rear of pin 405 will not prevent a backward unit of movement of the pinion as the spring 115 permits the necessary relative movement between the pinion and its disk. In this manner possibility of preventing backward rotation of pinions when the totalizer is bodily moved rearward is prevented. The normal 120 relation of disk and pinion is resumed when the pinion is again rotated a single unit forwardly on the bodily return movement of the totalizer.

125 For the purpose of shifting the main totalizer rearwardly, and at the same time shifting shaft 203 rearwardly so that there shall be no relative movement between the pawl carrying shaft 203 and the main totalizer, the shaft 302 (Fig. 1) which supports the totalizer carrying arms is connected to shaft 130

203 by arms 413 and these arms are provided with pins 414 extending through slots 415 in levers 416 pivoted to the machine frame by pins 417 and at their lower ends 5 having rollers 418 to be engaged by cam grooves 419 cut into cam disks 420 fast to drive shaft 2. The cams 420 are so positioned on shaft 2 as to rock arms 416 to carry the main totalizer rearwardly at the moment 10 that the actuators 200 reach their home positions as shown in Fig. 1 and accordingly if the actuators are moved the extra unit farther rearwardly such extra unit of movement will not cause rotation of the main to- 15 talizer pinions but will effect the desired transferring operation in the department totalizer then being operated. Then after the department totalizer has been disengaged from the actuators the main totalizer is re- 20 turned forwardly by operation of cams 420, thus a transfer in the main totalizer may be effected or not, depending upon the angular setting of pawls 403. For instance, consider- 25 ing a single denominational section, if a transferring operation takes place in a department totalizer only, then during the actuation of such totalizer the extension 406 on one of its disks 400 will engage pin 405 rocking pawl 404 in a counter clockwise di- 30 rection and during this rocking movement of the pawl, projection 410 thereon enters notch 409 in disk 401. At other times re- 35 spectively before and after the rocking of pawl 404, the curved surfaces 407 and 408 of the pawl by engaging the periphery of disk 401 prevent rocking movement of the pawl. When the actuator 200 reaches its normal position instead of being stopped by pawl 404 it is permitted to move farther 40 rearwardly one unit because of the angular position of pawl 404 while for the same reason its companion slide 201 is held back one unit. While the extra movement is taking 45 place in actuator 200 the main totalizer is moved rearwardly thus the extra movement does not take effect in it. The department totalizer is then disengaged from the actuators 200 and the main totalizer is returned to its normal position together with the shaft 50 203 and pawls 403 supported thereby. During this forward movement the pawl 403 engages pin 411 thereby restoring the actuator 200 and preventing a relative movement between the same and the main totalizer. In 55 the above manner the transfer operation takes place in the department totalizer only.

If the transferring operation is to take place in the main totalizer only, the operation will be that, while the pawl 404 serves 60 to prevent the required extra movement of actuator 200 while a department totalizer is engaged, the pawl does not prevent such extra movement after the disengagement of the department totalizer, when such move- 65 ment takes place and the required trans-

ferring operation is effected in the main totalizer. Assuming that during the restoring movement of actuators 200 the extension 406 of one of the disks 400 of the main totalizer engages pin 405 on one of pawls 403 the 70 angular position of the pawl will be altered so that its upper shoulder 421 will be moved forwardly into position to engage pin 412 on slide 201 before the slide reaches its home position but this engagement does not take 75 place because as the slide 201 reaches the point where the pin 412 would engage shoulder 421 the main totalizer and shaft 203 are moved rearwardly by cam 420, consequently pawls 404 will serve to stop slides 200 and 80 201 in their normal position and accordingly the rearward movement of the main totalizer causes it to move relatively of rack 216 and thereby to be rotated backwardly one unit. The department totalizer is then disengaged 85 and the main totalizer returned to normal position, but as the pawl 403 has been rocked to effect a transferring operation its shoulder 421 will, during the forward movement, engage pin 412 forcing the slide 201 one 90 space forward of its normal position and thereby through pinion 210 causing the slide 200 to move rearwardly an extra unit. The rearward movement of slide 200 and the forward movement of the main totalizer causes 95 the totalizer pinion to be rotated in a forward direction two units, consequently adding to the totalizer the unit which had been subtracted from it on its rearward movement and also adding the unit required for 100 effecting the transfer. The main totalizer is then disengaged from the actuators and such of pawls 403 and 404 as were displaced to effect carrying are restored to normal position, and for this purpose means are 105 provided for rocking shafts 203 and 205 in order that the sides of notches 422 therein may engage lugs 423 on the pawls 403 and 404 and restore the pawls to their normal angular position. The pawls on such re- 110 storing movement by engaging pins 412 restore displaced slides 201 and through pinions 210 restore the slides 200. For the purpose of rocking shafts 203 and 205 they are each provided with an arm 424 to which 115 are pivoted pitmen 425 having their lower ends forked over drive shaft 2 to be guided thereby. Each of the pitmen has a roller 426 extending into a cam groove 427 in a disk fast to shaft 2 and before the actuators 120 200 move rearwardly to actuate the totalizers the cam grooves 427 become effective to force pitmen 425 upwardly and thereby rock shafts 203 and 205 so that their slots 422 will not interfere with movement of pawls 125 403 and 404. At the very end of operations of the machine the pitmen 425 are drawn downwardly thus causing the upper edges of notches 422 to engage the lugs 423 on the pawls restoring the pawls to normal posi- 130

tion. In this manner the pawls are caused to engage pins 411 on actuators 200 restoring the same to normal position and through the pinions 210 restoring the companion slides 201.

When a transfer occurs in both the main totalizer and a department totalizer both pawls 403 and 404 will be rocked and their shoulders 421 will be engaged by pins 412 on slides 201 one unit before the slides reach home positions and thus compel pinion 210 to roll on rack 211 and thereby force the actuator 200 one unit rearwardly of its home position. Consequently the desired extra unit of movement will take place in the department totalizer but will not then occur in the main totalizer as at such time the main totalizer is being moved rearwardly. The department totalizer is then disengaged from the actuators and the main totalizer is returned to normal position thus causing it to move relatively of actuator 200 and thereby be rotated the desired extra unit. The main totalizer is then disengaged and the pawls 403, 404 and the differential slides are restored to normal position by oscillation of shafts 203 and 205.

Printing mechanism.—The object of the printing mechanism is to print in triplicate on insertel slips the amounts of transactions or totals, a character representing the department to which the transactions relate, a clerk's identifying number, the date and number of the transaction and a character representing the particular cash register employed.

The amount type carriers are set through gear connections with racks 216 (Fig. 1) consisting of pinions 500 fast to sleeves 501 encircling a shaft 502 and which sleeves carry pinions 503 (Fig. 19) meshing with gears 504 journaled on shaft 505. At the sides of gears 504 are gears 510 meshing with pinions 506 fast to sleeves 507 supported by a shaft 508 and carrying the type carriers 509 (Fig. 5). On a rod 511 are hung a pair of arms 512 which support at their lower end a shaft 513 on which are journaled a number of broad pinions 514 adapted by engagement therewith operatively to connect gears 504 and 510, and thus afford connections whereby the racks 216 may set the type carriers but also providing for independent return of the racks. A pitman 515 is provided connecting shaft 513 with a cam 516 fast to drive shaft 1, the pitman having a roller 517 for this purpose in engagement with a cam groove 518 in the cam. The cam groove is so formed as to engage broad pinions 514 with gears 504 and 510, on the forward movement of the differential mechanism and consequently its differential movement will be transmitted by the above described gearing to the type carriers 509. The cam also serves to hold

broad pinions 514 out of engagement during the return of the differential racks 216, at which time the type carriers remain in differentially set positions and impressions are taken.

To provide means for finally returning the type carriers, gears 504 and 510 have circular slots 519 through which extends a rod 520 carried by a pair of arms 521 fast to a shaft 505. Also fast to shaft 505 is a pinion 522 meshing with a rack 523 which is slotted at its lower end to be guided by the drive shaft. The shaft 1 is provided with a cam 524 for engaging a roller 525 on rack 523 and this cam is effective to position the rack as shown in Fig. 19 at the end of each operation of the machine. Consequently from the above construction, cam 524 first moves away from roller 525, then rotation of gears 504 and 510, when the type carriers are set through rod 520 rocks shaft 505 clockwise thus through rack 523 lowering roller 525 into the path of cam 524, then the movement of rack 523 under the action of cam 524 causes shaft 505 to be rocked in a counter clockwise direction, thereby engaging rod 520 with the ends of slots 519 in the gears 510 which have been displaced from normal position during the operation. As these gears are directly connected to the type carriers the type carriers will be restored to normal position.

For the purpose of printing on sales slips a character to identify clerks making transactions, detachable keys 526 (Fig. 6) are provided having identifying type engraved on their lower ends. These keys are insertible in a recess 527 in a tie bar or bracket 528. A pawl 529 pivoted to the tie bar 528 serves to retain the inserted key in place and also to compel the proper insertion of the key by coöperating with notches 530 and 531 in the keys and for which purpose the pawl is provided with shoulders 532 and 533. A spring 534 urges the pawl into engagement with notch 531, therefore to withdraw the key 526 it is necessary to rock the upper end of pawl 529 toward the key. In inserting a key the same cannot be pushed inwardly so that its notch 531 passes below shoulder 533 of the pawl as the inclined side of the notch serves to cam the lower end of the pawl forwardly and thereby carry its shoulder 532 into engagement with notch 530.

A type wheel 590 representing departments is differentially set by rack 591 on slide 220 (Fig. 3), for which purpose the rack meshes with a pinion 592 on shaft 593 to which is also fast a pinion 594 (Fig. 19). The latter pinion meshes with an intermediate gear 595 (Fig. 5) which communicates the movement through one of gears 504, a pinion 506, on shaft 508, to the department type carrier 590.

- When totals or subtotals are printed a type wheel 589 is set to cause the impression to include a character indicating that the amount is a total or a subtotal and relates to the main or department totalizers. This type carrier is set as are the amount type carriers through means of one of sleeves 501 and connections shown in Fig. 19. For this purpose one of sleeves 501 (Fig. 2) carries fast a gear 596 and this gear meshes with a rack 597 cut in slide 245, the differential operation of which is controlled by the total keys.
- Bracket 528 (Fig. 5) carries a type 598 by means of which the machine is identified with all impressions made by it.
- The form of slip which the printing mechanism is adapted to operate on is shown in Fig. 21. It will be seen from this figure that records of transactions are printed in triplicate on the slip, the amounts of the transactions being at the right and next is a character representing the department to which the transaction relates, to the left of this character is the clerk identifying character, then a number representing the cash register employed to print the slip, then the date and finally the consecutive number of the transaction.
- The slip supporting table 535 is shown in Fig. 6 and is detailed in Fig. 17. The supporting table is immovable in the machine but coöperating with the table 535 is a stop device 536 for the slip which normally serves to limit the downward movement of the slip when inserted, but is rockable downwardly out of the path of the slip to permit the slip being fed by the machine to receive duplicate impressions on different lines. The table 535 is provided with flanges 537 at its sides for preventing relative sidewise movement of an inserted slip and has openings 538 through which feed rollers 539 project. The table 535 also has an opening 540 through which platen 541 passes when taking impressions. The table also has a pair of slots 542 through which project from underneath the table flanges 543 on the adjustable stop 536.
- The adjustable stop 536 is made in two parts 544 and 545. The part 544 is in the shape of a lever pivoted on a rod 546 and connected to the part 545 by a pin 547 passing through one of holes 548 in such part. At the forward end of the member 544 is a roller 549 which is in position to be engaged by a cam 550 fast to the feed roller supporting shaft 551. A spring 554 serves to urge the device 536 to rock around rod 546 so that its roller 549 is held in engagement with the cam 550. The member 545 has a handle 555 by which it may be sprung outwardly and disengaged from pin 547. It may then be shifted relatively of the member 544 permitting the pin 547 to engage some other one of the holes 548 in the member 545. In this manner the flanges 543 are adjustable with respect to the slip supporting table 535 for the purpose of accommodating the printing mechanism to different lengths of sales slips. By positioning the pin 547 in hole 556 flanges 543 are placed below the plane of table 535 and thus slips of unusual lengths may be inserted in the printing device.
- The means for feeding slips is shown in Fig. 6 and detailed in Fig. 20. It consists of a pair of rollers 539 fast to shaft 551 which is journaled in the machine frames and also carries fast a pinion 558 meshing with a segment gear 559 pivoted to the machine frame by pin 560. The segment gear 559 is provided with a roller 561 fitting in a groove 562 in a cam disk 563 fast to drive shaft 1. Feed rollers 564 coöperate with feed rollers 534 and are journaled on a rod 565 carried by a pair of arms 566 fast to shaft 546. Extending downwardly from shaft 546 is an arm 567 fast to the shaft and is provided with a flange 568 extending across the rear edge of the arm 569 journaled on shaft 546 and provided with a roller 570 extending into a groove 571 in disk 563. The grooves in disk 563 are so formed as to first rock arm 569 outwardly, thereby causing it to engage flange 568 and consequently rock feed rollers 564 into engagement with feed rollers 557, then after the first impression, segment 559 is rocked to feed the sales slip downwardly in order to bring the uppermost impression line of the slip opposite the type carriers. The second impression is then taken and segment gear 559 is returned half way to normal position when the third and central impression is taken.
- In order that flanges 543 do not interfere with the feeding of the sales slip the device 536 is permitted to rock downwardly at the required time by cam 550 (Fig. 18) on the feed roll supporting shaft 551, rocking clear of roller 549.
- At the time the third impression is taken the part of the slip containing the bottom impression is severed from the remainder of the slip by a knife 572 (Fig. 6). The knife is slidably mounted in guides 573 and carries a rack 574 meshing with a segment gear 575 fast to a rod 576 journaled in the frames of the machine. An arm 577 is fast to rod 576 and at its lower end is pivoted to a pitman 578 supported at its rear end by drive shaft 1 and having a roller 579 extending into a groove 580 in a disk 581 fast to the drive shaft. Reciprocation of the pitman under the action of disk 581 oscillates segment gear 575 thereby raising knife 572 above a coöperating fixed knife 599 and then lowering it and severing the stub part of the slip from the body portion.

The platen 541 is carried by a frame 582 pivoted on shaft 546 and rigid with an arm 583 to the rear end of which is pivoted a pitman 584 supported by drive shaft 1 and having a roller 585 extending into a groove 586 in a disk 587 fast to the shaft 1. The groove 586 is suitably formed to actuate the platen to effect the three impressions.

In order to prevent interference between the platen 541 and the arms 536 (Fig. 17) of the slip stop device, either when the device is rocked downwardly, as above described or when the platen is driven up through the opening 540 in the slip table to take an impression, the platen and its carrying frame 582 are slotted as at 5411 (Fig. 5).

The ink ribbon for the printing mechanism is indicated by numeral 588.

Mechanism employed in total and subtotal printing.—Total and subtotal printing is accomplished by engaging the desired totalizer with the actuators and then releasing the latter and driving the same forwardly. The extents of movement of the actuators are controlled by the totalizing devices, and, therefore, it is necessary to prevent the depression of value keys and consequently to provide separate means for releasing the actuators.

On total printing operations the bank of total keys in connection with the department keys serve to select totalizers for operation, that is the total keys determine whether the main totalizer or one of the department totalizers is to have its total printed and the department keys determine which one of the department totalizers is to have its total printed. Therefore, when a total is printed from the main totalizer, in operating the machine it is only necessary to depress the appropriate total key and rotate the crank handle 4. As previously explained the bank of total keys is provided with means for rocking shaft 130 (Figs. 2 and 3) and thereby releasing the machine for operation.

The differential mechanism under the control of the total keys (Figs. 2, 15 and 16) serves to differentially position pitmen 249 and 261 so that the same may be engaged at their pins 257, 258, 267 or 268 by pitmen 255 or 256 which respectively have flanges 594, 595 and 596 and 597 for engaging the pins. Thus one of the pitmen is made effective with respect to either the main totalizer or the department totalizers to mesh the same with the actuators. The pitman 255 is employed on subtotal printing operations while the pitman 256 is employed on total printing operations. Both pitmen are vertically movable and are guided by shaft 2 and a fixed pin 598, and cam 2588 is suitably formed to move its respective pitman upwardly and hold it in its upward position during the greater part of the opera-

tion of the machine so that the particular one of pitmen 249 or 261 with which it is in engagement will hold its respective totalizer in mesh with the actuators during their forward and return movements. Consequently a subtotal will be printed as the amount of reverse rotation imparted to the totalizer pinions for the purpose of setting the type carriers is returned to the same by forwardly rotating the totalizer pinions an equal amount. Cam 2599 is formed to lift and hold in its upper position the pitman 256 only during the forward stroke of the actuators, consequently the selected totalizer will be reset.

To release the actuators 200 (Fig. 1) on total printing operations all of pawls 116 for the amount banks are rocked downwardly out of the paths of pins 122 on the actuators 200. To this end the depression of a total key in moving the detent 138 (Fig. 11) forwardly, through the pin 151 rocks lever 149 forwardly. As previously mentioned the lever 149 carries a pin 148 passing through a slot 147 in the pitman 143. The pin 148 also passes through a slot 147 in the pitman 599 and pitman 599 is provided with a slot 600 for co-operating with pin 142 on the arm 140 fast to shaft 117. Pitman 599 has a roller 601 extending into a groove 602 in a disk 603 fast to drive shaft 1. The groove 602 is suitably formed to draw pitman 599 downwardly on the beginning of each operation of the machine and hold the same downwardly during the greater part of the operation. When a total key is depressed the forward rocking of arm 149 carries pitman 143 out of engagement with pin 142 and positions pitman 599 into engagement with the pin; then the downward movement of pitman 599 under the action of cam 603 rocks shaft 117 in a counter clockwise direction, thereby causing arms 139 (Fig. 1) to engage the yoke shaped ends of pawls 116 rocking the same downwardly out of engagement with pins 122 and in this manner actuators 200 are free to drive the totalizer pinions to zero position and consequently set the type carriers for printing the total.

To provide means for compelling movement of actuators 200 against resistance offered by a totalizer when being reset, movement of slides 201 is prevented until the totalizer pinions arrive at zero, after which slides 201 are permitted to move to expend the remainder of movement of pinions 210. To accomplish this, pin 188 (Fig. 2) on the detent 138 for the total bank passes through a slot 604 in a pitman 605 having a roller 606 extending into a groove 607 in a disk 608 fast to shaft 2. The pitman also has an L shaped slot 609 through which passes a pin 610 on an arm 611 fast to shaft 204. The pitman is normally in

such position that its reciprocation by cam 608 does not cause the pitman to rock arm 611, but when a total key is depressed the pitman is rocked forwardly thus causing the 5 rear end of slot 609 to engage the pin 610 and then when the pitman is reciprocated, arm 611 will be rocked, consequently rocking shaft 204. The shaft 204 carries fast 10 a pair of arms 612 (Fig. 7) supporting rods 613 and 614 extending through slots 615 and 616 in levers 617 and 618 respectively loose on shafts 203 and 205. Each set 15 of levers 617 and 618 are equal to the number of elements in the totalizers and each lever has an extension 619 with a curved 20 surface for co-acting with a curved cut 620 in a disk 402 fast to the corresponding totalizer pinion. The levers 618 have rearward extensions 621 which carry rollers 622 25 for co-operating with extensions 623 of racks 211 for which purpose the extensions 623 have beveled ends 624.

In printing the total the main or department totalizer total key is depressed, thus 25 selecting either the main totalizer or the department totalizers for operation. If the department totalizers are selected then it is necessary in addition to depress one of the department keys thereby selecting a particular department totalizer in the usual 30 manner. The depression of a total key also makes pitman 599 effective with respect to arm 140 (Fig. 11) and when crank 4 is rotated the pitman will be lowered, thereby 35 rocking shaft 117 and disengaging pawls 116 from the actuators 200. Continued rotation of the drive shaft through cams 215 (Fig. 1) rocks arms 208 forwardly thereby carrying the actuators forwardly and resetting 40 the selected totalizer.

The extent of forward movement of actuators 200 is controlled by the selected totalizer. On the depression of a total key, pitman 605 (Fig. 2) is made effective with 45 respect to arm 611 on shaft 204, consequently before the actuators 200 are driven forwardly pitman 605 is lifted and causes the rocking of shaft 204 in a clockwise direction. This rocking movement of the 50 shaft through levers 612 (Fig. 7) results in rocking levers 617 and 618 in a counter clockwise direction bringing pins 622 into stopping position before stops 623 on slides 201, and causing their extensions 619 to engage the edges of disks 402. On the reverse 55 rotation of the totalizer pinions when the curved cuts 620 on the disks 402 arrive opposite the curved edges of extensions 619 said extensions are then free to rock into 60 the curved cuts 620. The totalizer pinions are at this time stopped in zero positions by pins 6192 on the totalizer drums engaging lugs 6191 on levers 617 or 618, thus preventing 65 the actuators 200 from further forward movement, consequently continued forward

movement of shaft 206 causes the pinions 210 to roll along racks 212 driving the slide 201 the complement of the movement of slide 200. Roller 622 being in the path of movement of extension 623 of rack 211 on 70 slide 201 prevents forward movement of the slide 201 until the extensions 408 enter the cuts 620. A rocking movement of pawls 403 and 404 when engaged by extensions 406, on the arrival of pinions to zero position on 75 total printing operations, is prevented by their curved edges engaging disks 401 and also by the edges of cuts 422 in shafts 203 and 205 which as usual engage lugs 423 on the pawls and are rocked for this purpose 80 by pitman 425 (Fig. 1).

Modifications.—Figs. 22 and 23 are details showing a rearrangement of the mechanism provided with indicators and means for setting the same. The keyboard 85 and the differential mechanism is substantially the same in operation as that previously described but in the modified form the totalizer actuators 708 have rack teeth 700 for driving a totalizer 701 supported by an 90 immovable shaft 702. The actuators are geared to the totalizer pinions through pinions 703 fast to companion gears 704 which are connected in one direction of movement of the actuators 708 to gears 705 of equal 95 diameter through the broad pinions 706 carried by a rockable frame 707. Means for rocking the frame is omitted but it will be understood that it is rocked to hold the broad pinions in mesh with gears 705 and 100 706 during either the forward or return stroke of the actuators 708. The actuators 708 and their companion slides 709 are driven by pinions 710 journaled on rock shaft 711 which is reciprocated in a vertical 105 direction by means of a cam 712 (Fig. 23) on the main drive shaft 713. A pitman 714 pivoted to the frame of the machine by a pin 715 is provided with a pair of rollers 716 for co-operating with the cam 712 and 110 at its lower end is pivoted to a link 717 connecting the pitman to an arm 718 fast to shaft 711. Also fast to the shaft is a segment gear 719 meshing with a fixed rack 720. Consequently when the pitman 714 is 115 rocked around pivot 715 segment 719 is compelled to roll up and down rack 720 and thereby cause the vertical reciprocation of the shaft 711. During this movement of the shaft the pinions 710 drive the actuators 708 120 and their companion slides 709 as controlled by the keys 721.

The keys, through their detent 722, cause pawls 723 to release actuators 708 when the keys are depressed. After an operation the 125 pawls 723 are restored to normal position by a pitman 724 which is operated by a groove 725 in a cam disk 726 on drive shaft 713. The pitman is pivoted at its lower end to an arm 727 fast to shaft 728 which sup- 130

ports the pawls 723 and the shaft 728 also carries a plurality of arms 729 for engaging the yoke shaped ends 730 of the pawls when the pitman is reciprocated. The operation 5 of this mechanism is similar to that employed in the machine previously described.

Pivoted to actuators 708 on pins 731 are levers 732 which, at their rear ends, are connected by pins 733 to indicator setting racks 10 734, the pins 733 passing through horizontal slots 735 in the racks. A rod 736 passes through curved slots 737 in the levers 732 and through vertical slots 738 in the racks 734 serves to guide the levers and racks in 15 their movements.

At about the center of levers 732 are rollers 739 which pass through slots 740 and 20 741 in arms 742 and 743 pivoted at their lower ends to arms 745 and 746 fast to a shaft 747. The shaft 747 also carries fast an arm 748 to the forward end of which is pivoted a pitman 749. The pitman is slotted at its upper end to be guided by drive shaft 713 and is provided with a roller 750 extending into a groove 751 in a disk 752 fast to drive shaft 713.

The indicator setting racks 734 mesh with pinions 753 fast to drum indicators 754. The racks 734 also mesh with pinions 755 by 30 which movement of the racks may be communicated to a second set of indicators not shown.

For alining and locking the indicators when in their set positions alining pawls 756 35 coöperate with notches 757 in the rear of the racks 734. The pawls are fast to a shaft 758 to which is also secured a forwardly extending arm 759 having a roller 760 which is engaged by a groove 761 in cam 752.

40 In operation, the upward movement of actuators 708 serves to rock levers 732 around their pivots 733 or around their pivots 739, depending upon at which point the greatest resistance is offered, the object 45 being simply to differentially set the pivot 731. While the actuators 708 are being differentially adjusted upwardly cam 752 lowers pitman 749 thus rocking shaft 747 counter clockwise causing either the upper 50 end of slot 741 or the lower end of slot 740 to engage roller 739 and thereby aid actuators 708 in or by themselves angularly adjusting levers 732 and through the racks 734 adjusting the indicators. While the actuators 55 are at rest in their differentially moved positions the alining devices 756 are engaged with the notches 757 in racks 734 retaining the racks in their adjusted positions. The actuators 708 are then restored

60 to normal position and the pitman 749 is also restored to normal position bringing the members 742 and 743 to the positions in which they are shown in the drawing. If, on the next operation of the machine, no key 65 is depressed the reciprocation of the mem-

bers 742 and 743 will restore the levers 732 to the position shown in the drawing and consequently restore the indicators to zero setting, but if some key is depressed the members 742 and 743 will position the indicators in conjunction with the actuators 708.

Operation.—To enter a record of the transaction one of the sales slips shown in Fig. 21 is inserted in the slip receptacle 735 (Fig. 6). The amount keys representing 75 the amount of the transaction, are depressed and the appropriate department key is depressed and finally crank handle 4 is given two revolutions resulting in rotation of the drive shafts 1 and 2. Rotation of shaft 1 causes cams 215 (Fig. 1) and 229 (Fig. 3) to rock the arms 208 and 225 forwardly. Slides 219 and 220 under the control of the department keys 125 (Fig. 3) are differentially adjusted by the forward movement 80 of arm 225. One or both slides are driven forward until one of the slides engages a depressed department key when the complement of the movement is taken up by the remaining slide because of rotation of pinions 223 along the rack 221 or 222 of the slide which has been stopped. In this manner rack 237 is adjusted forwardly or rearwardly depending upon its previous setting and whether or not rack 231 or the rack 237 85 is engaged by the ends of slots 230 or 234. Movement of the rack 237 causes rotation of pinion 239 which meshes with the pinion 243 rigid with the totalizer reel and consequently the reel is adjusted so that a desired 90 department totalizer is positioned opposite the actuators 200 (Fig. 7). The forward movement of arms 208 causes rod 206 to move forwardly and thus drive the slides 200 and 201 forwardly as controlled by the value 100 keys, the depression of which also serves to release the slides. When one of the shoulders 217 on slide or actuator 200 engages the shank of a depressed key the complement of the total possible movement 105 of the actuator is taken up by slides 201 as pinions 206 are caused to roll along racks 212 and thereby drive the slides 201 forwardly. In this manner the actuators 200 are differentially adjusted as desired. While the actuators 200 are at rest in their 110 adjusted position the main totalizer 251 and a selected department totalizer 351 are engaged with the actuators by upward movement of pitmen 249 and 261 (Fig. 2). The 115 details of the mechanism for operating pitmen 249 and 261 were previously pointed out. After the totalizers are meshed the differential mechanism is restored to normal 120 position by a rearward movement of rod 206 (Fig. 7) thereby causing the amount of the transaction to be added to the totalizers.

The amount type carriers in the printing mechanism are set through the differential rotation of sleeves 502 (Fig. 1) on the for- 125 130

ward movement of actuators 200. While the actuators are at rest in their moved positions the type carriers are disconnected from the same by disengaging broad pinions

5 514 (Fig. 19) from the gears 504 and 510. The three impressions are taken in succession on the inserted slip while the main differential mechanism of the machine is being restored. The first impression is taken on 10 the lower end of the slip after which the slip is fed downwardly and the upper impression is taken, then the slip is partly returned and the middle impression is taken and simultaneously the part of the slip containing 15 the lowest impression is severed from the remainder of the slip.

In total and subtotal printing the operation is different than when items are entered, in that no value keys are depressed 20 and the totalizer meshing mechanism is operative to hold in engagement the selected totalizer, either during the forward stroke of the actuating mechanism only or during both the forward and return strokes. In 25 either case the totalizer is reversely rotated by the differential mechanism to its zero position at which time it controls the extent of movement of the differential mechanism and thereby the type carriers by the mechanism shown in Fig. 7 and previously pointed 30 out in detail.

While the form of mechanism herein shown and described is admirably adapted to fulfil the objects primarily stated, it is to 35 be understood that it is not intended to confine the invention to the one form of embodiment herein shown and described, as it is susceptible of embodiment in various forms, all coming within the scope of the 40 claims which follow.

What is claimed is:—

1. In a machine of the class described, the combination with a pair of complementary 45 movable members movable in the same direction, manipulative devices for controlling said members, a plurality of totalizing devices selected for operation by either of said members and means for actuating the selected totalizer.

50 2. In a machine of the class described, the combination with a pair of complementary movable members movable in the same direction, of a device for giving said members movements which combine to a 55 constant value, a plurality of totalizing devices selected for operation by either of said members, and means for controlling differentially the movement of one of said members.

60 3. In a machine of the class described, the combination with a plurality of totalizing devices mounted on an adjustable frame, of a pair of members adapted to differentially position said frame, said members mounted to be capable of relative move-

ment but to have together a movement of constant quantity and in the same direction, and means for regulating the extent of movement of said members.

4. In a machine of the class described, 70 the combination with a plurality of accounting devices mounted on a rotatable reel, actuators for the accounting devices, a support for each accounting device movable relatively of the reel for the purpose of operatively connecting an accounting device with the actuators, cams constructed to be effective at different times, and means for connecting for operation one of said supports and any desired cam. 80

5. In a machine of the class described, 85 the combination with a plurality of totalizers, of totalizer actuators, a supporting shaft for each totalizer, guide ways in which said shafts are movable, totalizer engaging mechanism having guide ways registering with said first mentioned guide ways, means for shifting the totalizers along said guide ways, and means for operating said engaging mechanism. 90

6. In a machine of the class described, 95 the combination with a plurality of totalizers, of totalizer actuators, a supporting shaft for each totalizer, a guide way in which said shafts are movable, engaging mechanism having a guide way registering with said first mentioned guide way, said guide ways together being continuous, means for shifting the totalizers along said 100 guide ways, and means for operating said engaging mechanism.

7. In a machine of the class described, 105 the combination with a totalizer, of totalizer actuators, a member operatively related to said totalizer for engaging it with said actuators, devices operative at different times for operating said engaging member, and means for connecting said engaging member with any one of said devices.

8. In a machine of the class described, 110 the combination with an accounting device, of means for differentially positioning said accounting device forwardly or backwardly, said means comprising a pair of complementary movable members movable in the 115 same direction and an actuator for the accounting device movable in opposite directions by the respective complementary movable members.

9. In a machine of the class described, 120 the combination with an accounting device, of a pair of complementary movable members having unidirectional movements, an accounting device actuator, and connections from said complementary movable members for moving said actuator in opposite directions. 125

10. In a machine of the class described, the combination with a rotatable reel on which are mounted a plurality of accounting 130

- devices, of accounting device actuators, a pair of complementarily movable members movable in the same direction, means actuated by the complementarily movable members for differentially rotating the reel forwardly or backwardly for the purpose of operatively associating any accounting device with the actuators, and keys controlling said complementarily movable members.
- 10 11. In a machine of the class described, the combination with a pair of complementary movable members, of a device for giving said members movements which combine to a constant value, means for controlling differentially the movement of one of said members, a totalizer adapted to be actuated by one of said members, and said totalizer controlling said complementary movable members to permit or prevent a certain unit 20 of movement of one of said members for the purpose of transferring.
12. In a machine of the class described, the combination with a totalizing device, of a pair of differentially but complementary 25 movable members which combined have a movement of constant value, one of said members being constructed to operate said totalizing device, and said totalizing device itself having means for determining in 30 which of said pair of members a unit of movement will occur.
13. In a machine of the class described, the combination with an accounting device, of a differentially movable element for actuating said device, and a stop not requiring springs for operativity controlled by said accounting device to limit the movement of said movable element.
14. In a machine of the class described, the 40 combination with an accounting device, of a springless element for actuating the accounting device, connections for positively driving said element different distances, and said accounting device controlling said connections for the purpose of effecting transfers.
15. In a machine of the class described, the combination with an accounting device, of a pair of complementary movable members one of which is adapted to operate the accounting device, a transfer device serving normally to stop said movable members in a certain relative position, and an element of said accounting device arranged to shift said transfer device.
- 55 16. In a machine of the class described, the combination with an accounting device, of a pair of complementary movable members one of which is constructed to operate said accounting device, manipulative devices for regulating the movement of said members in one direction, and transfer devices for regulating their movement in the opposite direction.
17. In a machine of the class described,
- the combination with an accounting device, 65 of a pair of members which are relatively movable but which together may be moved only a certain predetermined extent, a stop for preventing movement of one of said members, and an element carried by the accounting device for controlling the stop to permit it to release said member.
18. In a machine of the class described, the combination with a plurality of accounting devices, of a set of actuators coöperating therewith simultaneously to operate a plurality of accounting devices and independently to effect transfers therein.
19. In a machine of the class described, the combination with a plurality of accounting devices, of a set of actuators coöperating therewith simultaneously to operate a plurality of accounting devices and successively to effect carrying operations therein.
20. In a machine of the class described, 85 the combination with an accounting device, of a springless element for actuating the accounting device, connections for positively driving said element different distances, and said accounting device controlling said connections for the purpose of effecting resetting.
21. In a machine of the class described, the combination with an accounting device, of a pair of members which are relatively movable but which together may be moved only a certain predetermined distance, means for driving one of said members, and means controlled by the accounting device for stopping said driven member at different parts 90 of its stroke for the purpose of controlling resetting of the accounting device.
22. In a machine of the class described, the combination with an accounting device, 105 of amount printing type, a springless element for positioning the type, connections for positively driving said element different distances, and said accounting device controlling said connections.
23. In a machine of the class described, 110 the combination with an accumulating device, of type carriers, differentially reciprocable members connected to drive the accumulating device and type carriers, keys for controlling movement of said members, and an 115 independent means for restoring the type carriers, said means being differentially adjusted when the type carriers are driven and returned to normal to restore the type carriers.
24. In a machine of the class described, the combination with an accumulating device, of type carriers, differentially reciprocable members connected to drive the type carriers on their forward movement and to 125 drive the accumulator on their return movement, and an independent means for restoring the type carriers, said means being dif-

- ferentially adjusted when the type carriers are driven and returned to normal to restore the type carriers.
25. In a machine of the class described, the combination with an accounting device, of an actuator therefor, and means for effecting accounting operations by both moving the actuator relatively of the accounting device and the accounting device relatively of the actuator while engagement is maintained between the accounting device and the actuator.
26. In a machine of the class described, the combination with accounting devices, of a mechanism for operating the accounting devices, a plurality of banks of keys for controlling said mechanism, a notched shaft common to said banks of keys, and key detents operative through said keys, said detents coöoperating with said notched shaft to either rock said shaft or prevent it from rocking.
27. In a machine of the class described, the combination with differential mechanism, of a plurality of totalizers arranged with the differential mechanism to be simultaneously operated thereby, one of said totalizers having denominational elements consisting of two parts one of which is driven by the differential mechanism and serves to drive the other part, connections between said parts permitting the driven part to remain stationary while the driving part moves backwardly under the action of the differential mechanism.
28. In a machine of the class described, the combination with a totalizer, of a printing mechanism, differential mechanism for operating the totalizer and printing mechanism, said differential mechanism comprising a pair of complementarily movable members, means for driving said members, and a device controlled by the totalizer operating to prevent movement of one of said members until the totalizer is rotated to zero position by the other member and then to permit the first mentioned member to move complementarily to its companion.
29. In a machine of the class described, the combination with a totalizer, of a printing mechanism, differential mechanism for operating the totalizer and printing mechanism, said differential mechanism comprising a pair of complementarily movable members, a device normally preventing movement of one of said members, and said totalizer and said one member coöperating with said device to cause it to lock the totalizer when the latter arrives at zero position.
30. In a machine of the class described, the combination with a pair of movable members, of means for giving said members movements in the same direction, said move-
- ments combining to a constant value, a plurality of totalizers, an adjustable frame carrying the totalizers, a series of keys selectively depressible to stop both the movable members and thereby control their relative movements to selectively position the totalizers.
31. In a machine of the class described, the combination with a pair of members movable in the same direction, of an invariably moved device for giving said members a differential relative movement, a totalizer element adapted to be actuated by one of the movable members, and manipulative devices selectively adjustable into the path of the pair of movable members to determine the extent of the relative movement of said members and thereby the extent of actuation of the totalizer element.
32. In a machine of the class described, the combination with a movable support, of a plurality of totalizers carried thereby, a set of actuators common to the totalizers, a pair of complementarily moved members movable in the same direction and adapted to move the totalizer support directly and in either direction from one position to another to set any desired totalizer in operative relationship with the actuators, and manipulative devices for controlling said members.
33. In a machine of the class described, the combination with a movable support, of a plurality of totalizers carried thereby, a set of actuators common to the totalizers, a pair of complementarily moved members movable in the same direction and adapted to move the totalizer support directly and in either direction from one position to another to set any desired totalizer in operative relationship with the actuators, and a series of keys selectively operable to control said members.
34. In a machine of the class described, the combination with a movable device, of a plurality of totalizers carried thereby, a set of totalizer actuators, a pair of differentially and complementarily movable members movable in the same direction, means for giving said members differential complementary movements combining to a constant value, connections whereby the aforesaid movable device may be adjusted directly and in either direction from one position to another by differential complementary movement of the movable members to select any desired totalizer for actuation, and manipulative devices for controlling said movements of the movable members and thereby the adjustment of the totalizer carrying device.
35. In a machine of the class described, the combination with a rotatable reel, of a plurality of totalizers carried thereby, a set

of totalizer actuators, a pair of differentially and complementarily movable members movable in the same direction, means for giving said members differential complementary movements combining to a constant value, connections whereby the aforesaid rotatable reel may be rotated directly and in either direction from one position to another by differential complementary movement of the 15 movable elements whereby to position any desired totalizer opposite the actuators, and manipulative devices for controlling said movements of the movable members and thereby the rotation of the totalizer carrying reel.

36. In a machine of the class described, the combination with a differentially adjustable frame, of a plurality of totalizers carried thereby, a set of totalizer actuators, a 20 pair of differentially and complementarily movable members movable in the same direction, means for giving said members differential complementary movements combining to a constant value, connections 25 whereby the aforesaid movable device may be adjusted directly and in either direction from one position to another by differential complementary movement of the movable members whereby to establish operative relation 30 between the desired totalizer and the actuators, and a series of keys for limiting the movements of the movable members.

37. In a machine of the class described, the combination with a rotatable reel, of a 35 plurality of totalizers carried thereby, a set of totalizer actuators, a pair of differentially and complementarily movable members movable in the same direction, invariably moved means for giving said members differential 40 complementary movements combining to a constant value, connections whereby the aforesaid rotatable reel may be rotated directly and in either direction from one position to another by differential complementary movement of the movable members to establish operative relationship between the 45 desired totalizer and the actuators, and a series of keys selectively depressible into the path of the movable members to limit 50 the movements of said members and thereby control the extent and direction of rotation of the totalizer reel.

38. In a machine of the class described, the combination with a movable support, of 55 a plurality of totalizers carried thereby, a set of actuators common to the totalizers, a pair of complementary movable members, manipulative devices, an invariably moved element coöperating with the manipulative 60 devices to effect differential complementary movements of the movable members, said movements combining to a constant value, connections whereby the differential complementary movement of the movable elements will effect differential movement of 65

the aforesaid totalizer support whereby to position any desired totalizer in coöoperative relationship with the actuators, the manipulative devices and invariably moved element also coöperating to hold the totalizer support stationary during the actuation of the 70 totalizer.

39. In a machine of the class described, the combination with a movable frame, of a plurality of totalizers carried thereby, a 75 set of totalizer actuators, a pair of differentially stepped complementarily movable members, an invariably moved means for imparting movement to said members, a series of keys selectively depressible to engage the corresponding differential steps on the movable members whereby to control the differential complementary movements of said members, and connections whereby the differential movement of the totalizer carrying frame positions any desired totalizer in operative relationship with the actuators, the depressed key and the invariably moved means coöperating to hold the frame stationary during the actuation of the selected 80 totalizer.

40. In a machine of the class described, the combination with a rotatable reel, of a plurality of totalizers carried thereby, a set of totalizer actuators, a pair of differentially 95 stepped complementarily movable members, an invariably moved means for imparting movement to said members, a series of keys selectively depressible to engage the corresponding steps on the movable members 100 whereby to control the differential complementary movements of said members, and connections whereby the movable members rotate the aforesaid reel to position a desired totalizer in operative relationship with 105 the actuators, the depressed key and the invariably moved means coöperating to hold the reel stationary during the actuation of the selected totalizer.

41. In a machine of the class described, 110 the combination with a movable support, of a plurality of totalizers carried thereby, a totalizer operating mechanism common to the totalizers, a pair of complementarily movable members having a normal starting 115 point, an invariably moved device constructed to drive the complementarily movable elements differential extents from this normal starting point and then restore them to said point, connections whereby the movable members may move the totalizer support differentially in either direction and directly from one position to another to select any desired totalizer for operation, and a series of keys controlling the movements of the members and coöperating with the invariably moved device to hold the totalizer support stationary during operation of the selected totalizer.

42. In a machine of the class described, 120

the combination with a pair of members each differentially movable and the movements of the two combining to a constant extent, devices for driving the members, a movable support carrying a plurality of totalizers, a totalizer operating mechanism common to the plurality of totalizers constructed to enter items or reset a totalizer as desired, connections whereby the movable members will move the totalizer support directly and in either direction from one position to another to bring any desired totalizer in position to be reset by the actuators, and manipulative devices controlling the movement of the movable members, said manipulative devices and the driving devices coöperating to hold the totalizer support stationary during resetting or actuation of the selected totalizer.

43. In a machine of the class described, the combination with a plurality of totalizers, of a set of actuators coöperating therewith simultaneously to actuate a plurality of totalizers, and means whereby transfers may be effected in either or both of the totalizers by the actuators.

44. In a machine of the class described, the combination with a plurality of totalizers, of a set of actuators, means for engaging a plurality of totalizers with the actuators to effect operation of the totalizers, and means controlled by any engaged totalizer whereby transfers may be effected therein by movement of the actuators.

45. In a machine of the class described, the combination with a plurality of totalizers, of a set of actuators common thereto, means for differentially reciprocating the actuators, means for engaging a plurality of totalizers with the actuators to effect simultaneous actuation of said totalizers, means normally stopping the actuators at zero at the end of a reciprocation, means controlled by either totalizer for adjusting said stops to cause an additional step of movement of the actuators, and means whereby said additional step of movement will effect transfers in the totalizer which effected adjustment of the stops.

46. In a machine of the class described, the combination with a plurality of totalizers, of a set of actuators common thereto, means for engaging a plurality of totalizers with the actuators to effect simultaneous actuation of said totalizers, a set of transfer pawls for each totalizer normally stopping the actuators at zero, means carried by each totalizer for adjusting its transfer pawls to effect an additional step of movement of the actuators, and means whereby the additional step of movement of the actuators will effect transfers only in the totalizer associated with the adjusted transfer pawls.

47. In a machine of the class described, the combination with a pair of members

having complementary differential movements which combine to a constant value, an actuating rack carried by one of said members, a plurality of totalizers, means for engaging a plurality of totalizers with said rack for simultaneous operation, a set of transfer pawls coöperating with each engaged totalizer arranged to normally stop both of the movable members at a normal starting point, means carried by each totalizer for adjusting the associated transfer pawls to stop one member a step short of normal position thereby causing an additional step of movement of the actuating rack bearing element, and means whereby said additional step of movement will effect a transfer in but the one totalizer.

48. In a machine of the class described, the combination with a totalizer, of a set of actuators therefor, means for operating the totalizer by both moving the actuators relatively of the totalizer and the totalizer relatively of the actuators while engagement is maintained between the totalizer and the actuators.

49. In a machine of the class described, the combination with a totalizer, of a set of actuators therefor, means for operating the totalizer by movement of the actuators relative to the totalizer to enter items and by movement of the totalizer relative to the actuators to effect transfers.

50. In a machine of the class described, the combination with a plurality of totalizers, of a set of actuators, means for engaging a plurality of totalizers with the actuators for simultaneous actuation, means for imparting differential movement to the actuators and an added movement to effect transfers, means for moving one of the totalizers with the actuators during the transfer step of movement of the actuators whereby to prevent the transfer step from taking effect in the totalizer and then moving the totalizer relatively of the actuator to effect transfers.

51. In a machine of the class described, the combination with a totalizer, of a plurality of pairs of members, the members of each pair being relatively movable but together movable only a certain predetermined distance, means for driving one member of each pair, and means controlled by the totalizer for stopping said driven members at different parts of their strokes for the purpose of controlling the clearing of the totalizer.

52. In a machine of the class described, the combination with a pair of differentially movable elements, the sum of the movements of the elements being invariably the same, devices for driving the differentially movable elements, a type carrier differentially positioned through connections to one of said elements, means for taking impres-

sions from the type carrier, and manipulative devices controlling the differentially movable elements, said manipulative devices and the aforesaid driving devices coöperating to hold the type carrier stationary while the impression is taken therefrom.

53. In a machine of the class described, the combination with a pair of differentially movable elements, the sum of the movements 10 of the elements being invariably the same, devices for driving the differentially movable elements, a type carrier, connections whereby the type carrier may be differentially moved directly and in either direction 15 from one position to another by the differentially movable elements, a series of keys controlling the movable elements, said keys and the aforesaid driving devices coöperating to hold the type carrier stationary while an impression is taken therefrom.

54. In a machine of the class described, the combination with a totalizer element, of a pair of differentially movable members which together may be moved only a certain predetermined distance, a stop for preventing movement of one of said members, 25 and an element carried by the totalizer element for controlling the stop to permit it to release said member.

30 55. In a machine of the class described, the combination with a totalizer element, of a pair of differentially movable members

which together may be moved only a certain predetermined distance, the pair comprising an actuating member and a companion member, a normally ineffective stop and means carried by the totalizer element for releasing the stop after it has served its purpose.

56. In a machine of the class described, 40 the combination with a rack bearing member and a companion member, the members being differentially reciprocable and the sum of the two reciprocations being invariably the same, a totalizer element, means for engaging the totalizer element with the rack member during movement of the latter in one direction to enter items and in the opposite direction to set the element at zero, a normally ineffective stop for holding the 45 50 companion member stationary in clearing operations until the element is at zero, manipulative devices for rendering said stop effective, and means carried by the totalizer element for rendering said stop ineffective 55 when the totalizer element reaches its zero position.

In testimony whereof I affix my signature in the presence of two witnesses.

THOMAS CARROLL.
